US00D913386S

(12) **United States Design Patent** (10) Patent No.: **US D913,386 S**
Channer et al. (45) Date of Patent: **** Mar. 16, 2021**

(54) **MULTI-PURPOSE EXERCISE DEVICE**

(71) Applicants: **Ennevor Channer**, Gaithersburg, MD (US); **Faithlyn Channer**, Gaithersburg, MD (US)

(72) Inventors: **Ennevor Channer**, Gaithersburg, MD (US); **Faithlyn Channer**, Gaithersburg, MD (US)

(**) Term: **15 Years**

(21) Appl. No.: **29/687,406**

(22) Filed: **Apr. 12, 2019**

Related U.S. Application Data

(63) Continuation-in-part of application No. 15/669,482, filed on Aug. 4, 2017, now Pat. No. 10,279,208.
